UNITED STATES PATENT OFFICE.

JOHN E. GENN, OF CHICAGO, ILLINOIS, ASSIGNOR TO STEWART-WARNER SPEEDOMETER CORPORATION, OF CHICAGO, ILLINOIS, A CORPORATION OF VIRGINIA.

SPARK-PLUG.

1,315,298.

Specification of Letters Patent.

Patented Sept. 9, 1919.

Application filed August 15, 1918. Serial No. 249,940

To all whom it may concern:

- Be it known that I, JOHN E. GENN, a citizen of the United States, and a resident of the city of Chicago, in the county of Cook 5 and the State of Illinois, have invented certain new and useful Improvements in Spark-Plugs, of which the following is a specification, reference being had to the accompanying drawings, forming a part thereof.
- 10 This invention relates to means for dissipating excess heat from a spark plug employed in an internal combustion engine, and is also directed to a particular form of electrode especially adapted to work well at high temperatures. It consists in the features and elements hereinafter described, and shown in the drawings as indicated by the claims.
- 15 In the drawings:

- 20 Figure 1 is an axial section of a spark plug illustrating various details thereof embodying this invention.

- 25 Fig. 2 is a transverse section taken as indicated at line 2—2 on Fig. 1, for showing the shape and mounting of the electrode which is a detail of the invention.

- 30 The spark plug illustrated in the drawing comprises the usual metallic shell, 1, in which there is secured the porcelain insulator, 2, 35 having its enlargement 3, clamped between the shoulder, 4, of the shell, 1, and a gland or bushing, 5, screwed into the upper end of said shell with packing washers, 6 and 7, interposed. To assist in dissipating the excessive heat acquired by the shell, 1, from 40 the adjacent parts of the engine cylinder, the shell may be grooved to form cooling fins or ribs, 8.

- 45 But additional capacity for carrying off excessive heat is provided in the construction of the conductor member, 9, connecting with the central electrode, 10, carried in the porcelain insulator, 2. This conductor, 9, is formed of a tube having a neck, 11, at its lower end engaged with the grooved upper end of the electrode, 10, by rolling or crimping the metal of said neck into the groove, 12, of the electrode. By a similar expedient the central hub or neck, 13, of the 50 metallic cap, 14, is attached to the tube, 9, near its upper end, and the tube is longitudinally positioned in the bore of the porcelain, 2, by crimping the edge of the flange, 15, into an exterior groove, 16, in the 55 porcelain as shown. The bore in the por-

celain is made slightly larger than the exterior diameter of the tube, 9, and at the lower end the bore is slightly larger than the electrode, 10, to permit of rapid assembling, and the space thus formed is filled 60 with cement, 17, which serves to secure the conductor, 9, and electrode, 10, firmly in position, and forms a gas tight joint between the parts.

A small quantity of mercury in liquid 65 form indicated at 18 is placed in the tube, 9, and since the spark plug is practically always used in upright or approximately upright position this liquid mercury will flow to the lower end of the tube adjacent the 70 end of the electrode, 10, and in contact therewith. The upper end of the tube is then sealed by a screw plug, 19. As the electrode, 10, and the porcelain, 2, become heated, the mercury at 18 is vaporized and 75 the vapor rises, finally filling the tube, 9, completely; but coming in contact with the upper portion which is open to the outer air, the vapor gives off its heat to the metal of the tube and of the plug, 19, and is again 80 condensed, whereupon it falls to the lower end of the tube in liquid form to repeat the operation. The drawing shows a spherical shell, 20, adapted to serve as a terminal for connection with suitably designed spring 85 clips on the ends of the conductor wire by which the ignition current is transmitted to the spark plug. By perforating this shell, 20, by a number of apertures, 21, to permit the circulation of air therethrough, 90 it is made to serve as additional radiating surface for dissipating the heat transferred to the upper end of the tubular conductor, 9, and the screw plug, 19. It is evident, 95 however, that any other form of terminal such as a binding nut on the end of the conductor could be specially designed for the purpose of heat radiation, and indeed the shell, 20, may be considered primarily as a radiator and only secondarily as a conductor terminal and connecting member.

105 It is found by experiment that even if the mercury, 18, is entirely omitted from the tubular conductor, 9, the conductor itself will transmit a considerable quantity of heat from its lower end to its upper end and will radiate such heat more readily than if it were of solid construction. Being tubular instead of solid in cross-section, it has a 110 much larger surface in proportion to the

cross-sectional middle required for its function as an electrical conductor, and a portion of this area being exposed within the perforated terminal shell, 20, while other parts are in direct contact with said shell, it will be seen that quite effective radiation will be secured from this detail of construction alone. With the addition of the mercury at 18 the rapid dissipation of any undesirable quantity of heat is assured.

It is well recognized that where both electrodes are formed of wire, particularly where the grounded electrode carried by the skirt of the shell, 1, is of wire and bent to bring its point at the proper distance from the insulated electrode, 10, the effect of a high temperature in the combustion chamber is often to warp said bent electrode out of shape, thus varying the spark gap from that intended, and seriously interfering with the proper operation of the plug. A much preferable form of grounded electrode is shown in the drawings, comprising a flat disk, 22, of nickel or nickel alloy having one edge comprising a circular arc adapted to coincide with the cylindrical wall of the skirt of the shell, 1, when the disk is inserted in a transverse slot cut in said wall. The disk being inserted in the slot, it is secured therein by staking,—that is, by forming the metal of the rim of the skirt by means of a center punch or similar tool, so as to indent the surface of the disk, 22, at the point, 23, and drive into the indentation a portion of the metal of the skirt, as indicated in Fig. 1. The disk is formed with a hole at 24 adjacent the inner wall of the skirt of the shell, 1, and adapted to serve as a drain aperture for any oil which might become lodged on the upper surface of the disk, 22, and also to permit freer circulation of the gas about the electrode. As shown in Fig. 2, the curved edge, 25, of the disk, 22, coincides with the outer wall of the skirt of the shell, 15 while its straight edge, 26, formed upon a chord of the arc, 25, extends proximate to the electrode, 10, to form the spark gap. It will be understood that with an ignition current of relatively low intensity, the spark 50 will occur almost entirely at the point of

closest approach between the two electrodes; but with increasing intensity of the ignition current, the spark will tend to spread out along the edge, 26, of the disk, 22, thus distributing the wear on the disk and insuring a long term of service therefor.

I claim:

1. In a spark plug comprising an insulating member and an electrode carried therein, a conductor connected with said electrode 60 within the insulator and heat radiating means at the outer end of the conductor comprising a metallic shell of approximately spherical form secured in contact with said conductor adapted to serve as a connecting terminal therefor, and having its wall apertured to admit air to the inner surface of said walls for increasing its capacity for radiating heat, transmitted from the conductor.

2. In a spark plug comprising a metallic shell, an insulator mounted therein, and an electrode carried by said insulator, the shell terminating in a substantially cylindrical skirt surrounding said electrode and having 75 a transverse slot cut in from one side thereof near the end and a second electrode to operate with the first, comprising a flat disk secured in said transverse slot at one side only of the first electrode, an edge of said 80 disk extending proximate to said first electrode but spaced therefrom to form a spark gap.

3. In a spark plug comprising a metallic shell, an insulator mounted therein, an electrode carried by said insulator, the shell terminating in a substantially cylindrical skirt surrounding said electrode, a flat metallic member having one edge curved to approximately coincide with the outer wall of 85 said skirt and another edge extending through the space between the first electrode and the inner wall of said skirt proximate to said first electrode to form a spark gap, and an aperture in said flat electrode adjacent 90 the inner wall of the skirt.

In testimony whereof, I have hereunto set my hand at Chicago, Illinois, this 12th day of Aug., 1918.

J. E. GENN.
